ALFRED F. SMITH, OF PITTSBURG, PENNSYLVANIA, ASSIGNOR TO WYCKOFF, SEAMANS & BENEDICT, OF ILLION, NEW YORK, A CORPORATION OF NEW YORK.

TYPE-WRITING MACHINE.

No. 881,205.

Specification of Letters Patent. Patented March 10, 1908.

Application filed December 24, 1904. Serial No. 238,212.

To all whom it may concern:

Be it known that I, ALFRED F. SMITH, citizen of the United States, and resident of Pittsburgh, in the county of Allegheny and 5 State of Pennsylvania, have invented certain new and useful Improvements in Type-Writing Machines, of which the following is a specification.

This invention relates to typewriting machines and more particularly to those of the 10 rotary platen class.

The general object of the invention is to improve the facilities for commercial billing so as to afford an absolute check on the bills 15 rendered and accounts kept and for simplifying the work of the book-keepers of the establishment. To this end I associate with the platen corresponding to the usual platen of the machine, a second and auxiliary 20 platen. The two platens may be actuated separately and independently of each other, and it is in this manner that they are designed to be utilized in commercial billing work. Means are shown, however, by which 25 the two platens may be so connected that they may be actuated by the usual and ordinary line-space mechanism of the machine to which my invention is shown as applied, and when so coupled or connected the two platens 30 may be used as one in a manner in no wise different from that employed with the usual and ordinary platen of the machine.

One billing system in which the two platen are used in their separate and distinct capacities may be outlined briefly as follows:— 35 When a sale is made, a bill or sales slip containing the items and amounts of the sale is made out by the sales clerk and sent to the office of the establishment. At the end of 40 the day the sales slips which have been received at the office are divided into lots alphabetically, and the order in which each lot or group is assortied is thereafter maintained at all times. The various lots or groups then 45 pass into the hands of an operator of an adding machine who totals all sales slips of each customer, with the adding machine and then prints the several totals upon a totalizing strip in said machine. The totals will appear 50 on the totalizing strip of the adding machine in the order in which the sales slips are kept. The different lots of sales slips alphabetically grouped as stated are next turned over to the typewriter operators who make

from the sales slips the bills which are to be 55 sent to the customers. Thus one operator will have, for example, the bills of all customers whose names begin with A, B, C or D; a second operator will have the bills of all customers whose names begin with E, F, G 60 or H, and so on. The sales slips being carefully maintained in the order in which they were handed to the typewriter operator are used as copies from which to write the bill. The latter is inserted into the machine so as 65 to be fed over the long section of the platen or that section which may be said to correspond with the ordinary and usual platen of the machine. At the same time that the first bill is inserted in the machine a separate 70 and independent long and narrow strip of paper is inserted in the machine, so as to be fed over the short section of the platen.

After the entry of the day's sales on the bill is completed the total amount of the day's 75 sales is written by the operator in the daily total column on the bill and thereafter this total amount for the day is written on the narrow continuous strip on the short auxiliary platen. It will be apparent, therefore, 80 that the totals on the narrow strip, which may be called the checking strip, will appear in the order in which the typewriter operator receives the sales slips and in which the entries are made on the bills. After the day's 85 items have been written on it, the bill is filed away until the next sale is made to the customer to whom the bill is made out. This method is continued until the end of the month when the monthly total is made out 90 from the daily totals on the bill, after which the latter may be given to the book-keeper who makes his entries from it, and thereafter it is forwarded to the customer. When this course is pursued the condensed record carbon sheet usually employed may be dispensed with. At the end of each day the narrow checking or totalizing strip containing that day's totals of the different bills is turned over to the book-keeper for comparison 95 with the totalizing strip previously made on the adding machine. By comparing this latter strip with the checking strip of the typewriting machine, the successive amounts may readily be checked one by the other. The corresponding amounts of the two strips should agree identically in amount. 100 If they do not agree it is evident that a

mistake has been made. The error may be quickly located by going back to the original sales slip and the bill, and comparing the two latter. In order to trace the doubtful item back to the sales slip it is necessary only to count from the top of the checking strip; and if it be found, for example, that the doubtful item is the sixteenth from the top, then the operator counts down to the sixteenth sales slip from the top of the pile of sales slips to find the slip or slips bearing the daily total which is in doubt. Thereupon reference to the corresponding bill will indicate where and by whom the mistake was made. The typewritten checking strip and the adding machine totalizing strip are pasted in a book which is kept on file. The sales slips, still maintained in the original order, are filed away so that reference may conveniently be made to them at any time.

In the accompanying drawings, I have illustrated my invention as embodied in a typewriting machine having the general characteristics of the well known No. 6 Remington typewriter, but it is to be understood that I do not desire to be limited to the particular machine or the particular construction herein shown. The invention may be applied to other forms of writing machines and the construction and arrangement of the parts may be varied without departing from the spirit and scope of my invention.

In the drawings, Figure 1 is a view taken in side elevation of the upper part of a typewriting machine and showing so much of the machine as is necessary to illustrate my invention. Fig. 2 is a fragmentary top plan view of the right-hand side of the machine shown in Fig. 1. Fig. 3 is a sectional view taken on a plane represented by the line $z-z$ of Fig. 1 but omitting some of the parts on the carriage. Fig. 4 is a view of the platens in front elevation and showing a part of a written bill and a checking strip mounted thereon. Fig. 5 is a detail view showing in operative position the means for connecting the two platens.

Referring now to the drawings, 1 indicates the top plate of the machine, 2 one of the 50 posts supporting the back rail 3, 4 the shift rail at the front of the machine, 5 a platen frame or carrier comprising front and back bars 6 and side bars 7, and 8 a carriage truck with which the platen frame or carrier is connected by links 9, one of which only is shown in the drawings. Mounted at the front of the platen carrier is a roller 10 which co-operates with the shift rail 4, and supported in the carriage truck are rollers 11 (one of which 60 only is shown in the drawings) which co-operate with the back rail 3. The side bars 7 of the platen carrier support a platen axle 12 upon which is rotatably mounted a platen 13 comprising a wooden core 14 and an outer 65 covering 15 of rubber or other suitable ma-

terial. The platen 13, which may be termed the main platen has the general characteristics of the usual and ordinary platen, but its right-hand end is arranged or terminates considerably further from the right-hand side bar 7 than is the case with the ordinary form. As appears most clearly in Figs. 3 and 4, metal platen heads 17 are suitably secured to the wooden core 14 as by the usual wood screws 16. A set screw 17^a passes through the hub of the left hand platen head 17 (Fig. 4) and bears against the axle 12, thereby fixedly connecting said axle with the platen 13 and its heads 17. Integral with the right-hand platen head 17 is an elongated hub or sleeve 18. Near its outer end the sleeve 18 is considerably reduced in diameter, the junction of the reduced portion 19 and the larger portion forming a shoulder 20. The outer end of the reduced portion abuts 85 against the right-hand side bar 7 and for a short distance from the shoulder 20 the reduced portion is threaded at 21.

The sleeve 18 serves as a bearing for the short auxiliary platen 22 which comprises 90 essentially an inner wooden core 23, an outer sheath or cover 24 of rubber or other suitable material, and metal heads or end-pieces 25 and 26, said end pieces being secured to the wooden core by any suitable means such as 95 the usual wood screws 27. The heads or end-pieces of the auxiliary platen are perforated centrally so that said platen may be rotatably mounted upon the sleeve 18. It may be said that the main platen 13 is fixedly connected with the platen axle 12 so that their relation is fixed; and that the auxiliary platen 22 is mounted rotatably upon said axle so that their relation is a variable one. The cover 24 of the auxiliary platen slightly 100 overlaps the left-hand end piece 25 and the cover 15 of the main platen 13 terminates a short distance from the plane of the outer face of the right-hand platen head 17. When, therefore, the short auxiliary platen is 110 mounted in position, its cover 24 extends over and upon the outer portion of the periphery of the right-hand platen head 17. This construction breaks or covers the joint between the two platens and prevents dust 115 or grit from falling between them. The periphery of the right-hand end piece 26 of the auxiliary platen is formed with a series of ratchet teeth 28. A ratchet wheel 29 having a central threaded opening is screwed on the 120 threads 21 of the reduced portion 19 of the elongated sleeve 18 and until it abuts against the shoulder 20 and thereby becomes fixed in respect of said sleeve 18.

The ratchet wheel 29 is perforated at 30 to 125 receive a locking pin 31, and the end piece 26 is perforated at 32, the hole 32 being equal in diameter to and at the same distance from the center of rotation as the perforation 30 in the ratchet wheel 29. The locking pin 31 130

is provided with a knurled head 33 by which it may be conveniently manipulated. Integral with the pin 31 is a hub-like portion 34 which is provided with two oppositely disposed and inwardly projecting short pins 35, the ratchet head 29 being formed with recesses or depressions 36 to receive said last named pins. The locking pin 31 is constantly pressed inward by the force of a leaf spring 37, the end of which is bifurcated so that the arms 38 of the bifurcation embrace or partially surround the locking pin. The leaf spring is secured to the face of the ratchet wheel 29 by a headed screw 39.

15 The locking pin mechanism just described, when in operative position, as illustrated in Fig. 5, so connects the two platens that they may be operated by the usual and ordinary line-space mechanism presently to be described, but for the main purposes of my invention the locking mechanism is normally inoperative as shown in Figs. 2 and 3. To render the mechanism inoperative, as shown in these last named figures, it is necessary 25 only to pull the locking pin outward or toward the right against the pressure of the leaf spring 37 until the pins 35 are disengaged from the recesses 36, and thereafter to turn the knurled head 33 of the locking pin until 30 the said pins 35 are out of alinement with their recesses 36. If now the locking pin be released, the ends of the pins 35 will abut against the face of the ratchet wheel 29, thus preventing the locking pin from returning to 35 the position shown in Fig. 5. The pins 35 are of such length that when they abut against the face of the ratchet wheel 29, the end of the locking pin 31 is wholly withdrawn from the perforation 32 in the end piece 26, 40 so that the two platens may be turned separately and independently of each other. It is to be understood throughout the specification that the locking pin mechanism is in inoperative position, except where the contrary is specifically stated.

In the mechanism, as hitherto described, the ratchet wheel 29 serves the purpose of the usual and ordinary ratchet wheel found in the type of machine under consideration. Engaging with the teeth of said ratchet wheel is 50 a detent roller 40 which is mounted at the end of the spring finger 41, which is fixedly secured to the rear bar 6 of the platen frame or carrier. The usual form of line-space lever 42 is pivoted at 43 to a lug 44 fixed to the platen frame, and pivoted to the upper arm 45 of said line-space lever at 46 is a pawl 47 which co-operates with the ratchet teeth of the ratchet wheel 29, and the throw 55 whereof may be regulated by a line-space regulator 48. The line spacing devices are those common to the machine under consideration, and it is not deemed necessary to describe them in greater detail.

65 When the line-space lever 42 is operated in

the usual manner it causes the pawl 47 to engage with the teeth of the ratchet wheel 29 and to rotate the latter one, two or three teeth, as the case may be. As the ratchet wheel turns, it causes the sleeve portion 19 on which it is mounted and the sleeve 18 to rotate with it thereby rotating the main platen 13 through a corresponding distance. During this rotary movement of the main platen 13, the auxiliary platen 22 remains 75 quiescent.

Suitably secured as by screws 49 to the top of the front bar 6 of the platen frame are two upstanding ears 50 which serve as bearings for the pivot portion 51 of an auxiliary line-space lever 52. The line-space lever comprises, in addition to the pivot portion 51, a finger portion 53 projecting forwardly in a general horizontal direction from the left-hand end of said pivot portion and a rearwardly projecting horizontal arm 54. Pivoted at 55 to the end of the arm 54 is a depending pawl 56 which is adapted to engage with the ratchet teeth 28. The pawl 56 is formed with a tail 57 which is normally 90 pressed against a pin 58 projecting from the side of the arm 54 by a flat spring 59 which is also secured to said arm 54. The rear or pawl arm of the auxiliary line-space lever is held normally depressed, as shown in Fig. 1, 95 by a coiled spring 60 which surrounds the pivot portion 51 of the lever, and one end whereof is secured to the rear or pawl arm 54 of said lever. A roller detent 61 is mounted in a spring arm 62 which is fixedly secured to 100 the rear bar 6 of the platen frame. The roller detent 61 co-operates with the ratchet teeth 28 to prevent accidental rotation of the auxiliary platen.

In operation, the bill, which is indicated by 105 the reference *a*, is introduced into the machine so as to feed over the main platen 13. At the same time that the first of the day's series of bills is introduced into the machine, a long, narrow strip of paper, which has been 110 previously referred to as a checking strip and which is indicated in the drawings by the reference *b*, is introduced into the machine so as to feed over the shorter or auxiliary platen 22. Considering the bill *a* to be one well 115 along in the day's series of bills, it is evident that when the said bill *a* is introduced into the machine the checking strip *b* will have printed upon it a number of daily totals, as indicated in Fig. 4 of the drawings, and this 120 number will be the same as the number of bills which have been written up prior to the introduction of the bill *a*. As illustrated in the drawings, the bill *a* is one showing a prior purchase made on Nov. 5th and representing 125 a total for that date of \$51.50, which amount it is to be assumed was set down in the proper place on the checking strip of Nov. 5th. The bill is fed into the machine in a well-known manner, which I have not considered it nec- 130

essary to explain, until the proper position is reached for printing the first line of the purchase made on Nov. 12th, namely:—

Nov. 12, To 1 pr. of portières 75.00

The data is copied by the operator from the sales slip in a manner well understood and which I have not deemed it necessary to explain at length. Thereafter the line-space lever 42 is actuated, causing the pawl 47 to engage with the ratchet wheel 29, and turning the main platen 13 through a double line space, the line-space regulator 48 being so set as to give that amount of feed to the main platen, as indicated in Fig. 1. During this rotation of the main platen through two spaces, the auxiliary platen is maintained in a relatively fixed position or state of rest by the engagement of its detent roller 40 with the ratchet teeth 28. The second line of the purchase of Nov. 12th, namely:—

1 pr. lace curtains 15.50

is next written on the bill. Then the line space lever 42 is again actuated, the auxiliary platen remaining motionless as before, after which the total amount of the purchase, namely \$90.50, is written in the "daily total" column.

Let it be assumed that the auxiliary line space lever 52 has not been actuated since the last preceding amount was written on the checking strip, which amount (\$27, as appears in Fig. 4) it will be understood, is the daily total for Nov. 12th of the last preceding bill. The finger portion 53 of the auxiliary line space lever is next depressed, causing the auxiliary line space pawl 56 to engage with the ratchet teeth 28 and turning the auxiliary platen 22 one line space. The paper carriage, which term embraces the truck 8, carrier 5 and the parts mounted thereon, is next moved in letter space direction in a well known manner, until the column of figures on the checking strip *b* is in line with the printing point and thereafter the amount of the purchase, namely \$90.50, is written on said checking strip.

The bill *a* is now removed from the machine and filed away until the next purchase is made for the same account or until the end of the month. Thereafter the next succeeding bill is fed into the machine; the amount of the purchase of Nov. 12th is copied upon it from the sales slip relating to said succeeding bill in the manner hitherto described; and the total amount of the purchase is recorded in the daily total column of the bill.

The auxiliary line-space lever is thereupon actuated to cause a rotary movement of the auxiliary platen, thereby feeding the checking strip the distance of a single line space and the daily total is recorded under the \$90.50, which is the last amount on said

checking strip. This process is repeated until all of the day's bills have been written and their amounts recorded on the checking strip, which latter is then turned over to the book-keeper for comparison with the adding machine totalizing strip, as has been explained.

When it is desired to use the platen for ordinary work it is only necessary to manipulate the locking or coupling device; that is, to turn the locking pin 31 by means of its head 33 until the pins 35 aline with the recesses 36. When this position is attained the spring 37 pushes the locking pin inward. Either of the platens is rotated until the holes 30 and 32 are in alinement and as soon as this occurs the locking pin 31 will enter the hole 32, thereby locking or coupling the two platens together so that both will rotate together when actuated either by the ordinary line-space lever 42 or by the auxiliary line-space lever, or by the usual platen finger wheel 63. The axes of the two platens are coincident, and said platens are equal in diameter and are so closely arranged end to end that they afford a practically continuous cylindrical surface throughout their combined lengths. Consequently, if a sheet of paper approximating in width the length of the combined platens be fed into the machine, it may be manipulated by the line spacing devices described and by the other devices common to the machine and written upon as though the platen were one of the regular style.

It will be noted that the line space operating levers 42 and 52 are unequal in length, the power arm of the lever 52 being much shorter than the power arm of the operating lever 42 and that said operating levers are actuated in opposite directions, the lever 42 being pulled upwardly and the lever 52 being pressed downwardly. This arrangement is a desirable one as it tends to prevent confusion in the mind of the operator as to the line spacing devices and enables said line spacing devices to be independently operated without one interfering with the other.

Of course, the platens herein shown and described may be used for other systems of billing as well as for any and all other purposes for which they may be applicable; and I do not wish to be considered as limited to the use of my novel mechanism for the specific purposes above described, inasmuch as it is plain that said mechanism may be used for a variety of purposes. For example, where what may be termed the condensed record system is employed, the bill, as it is written is manifoldest by means of carbon paper on a "condensed record" or "sales sheet" which, after it is filled, is usually incorporated with other sales sheets in a binder, which binder then constitutes a sales

book. Each regular customer of the establishment is designated by a number or other arbitrary symbol and after the amount of his purchase is recorded on the bill, the same amount is written on the checking or ledger strip preceded by his arbitrary designation or symbol. When all of the day's sales have been recorded on the ledger strip, the latter is turned over to the book-keeper who is enabled, by means of the arbitrary symbols, to debit or credit the amounts to the proper parties in his ledger.

Where credits are to be given for cash or returned goods, such credits may be entered on the monthly bill sheet and on the checking or ledger strip in credit columns provided on said papers or sheets. This part of the account system has been omitted from the drawings and specification in order to simplify the presentation of the invention as much as possible consistently with a clear description thereof.

What I claim as new and desire to secure by Letters Patent, is:—

1. In a typewriter machine, the combination of a platen carrier; a platen axle having bearings in said platen carrier; a platen fixedly connected with said platen axle and carrying a ratchet wheel; a second platen 25 rotatably mounted on said platen axle; and also carrying a ratchet wheel, said two ratchet wheels always being maintained at a fixed distance from each other; line-spacing devices co-operating with the first named platen; separate line spacing devices co-operating with the second named platen; and a spring lock for connecting the two platens so that both may be simultaneously actuated by either of said line-spacing devices.

2. In a typewriting machine, the combination of a platen carrier; a platen axle having bearings in said platen carrier; a platen having a fixed relation with said platen axle; a ratchet wheel having a fixed relation with said platen axle; a second platen loosely mounted on said platen axle between said platen and said ratchet wheel; a second ratchet wheel having a fixed relation with said second platen; line-spacing devices co-operating with the first named ratchet wheel; line-spacing devices independently co-operating with said second ratchet wheel; a rotatable locking pin mounted on the first named ratchet wheel; and means whereby when 55 said locking pin is suitably rotated in its bearing on said first named ratchet wheel it is caused to enter a hole in said second ratchet wheel, thereby connecting the two ratchet wheels so that their respective 60 platens are caused to rotate simultaneously

under the actuation of either of said line-spacing devices.

3. In a typewriting machine, the combination of a platen carrier; a platen axle having bearings in said platen carrier; a platen 65 having a fixed relation with said platen axle; a ratchet wheel having a fixed relation with said platen axle; a second platen loosely mounted on said platen axle between said platen and said ratchet wheel; a second 70 ratchet wheel having a fixed relation with said second platen; line-spacing devices co-operating with the first named ratchet wheel; line-spacing devices independently co-operating with said second ratchet wheel; a 75 rotatable locking pin carried in a perforation in the first named ratchet wheel; a spring constantly pressing said locking pin towards said second named ratchet wheel; and means for controlling the longitudinal movement 80 of said locking pin so as to cause it either to be held disengaged from said second ratchet wheel or to cause it to engage with said ratchet wheel under the impulse of said spring.

4. In a typewriting machine, the combination of a platen frame, and a divided or sectional platen mounted thereon, said platen comprising a plurality of sections, each section comprising an interior core, a head and an exterior covering or sheath, the 90 sheath of one platen section overlapping the head of an adjacent platen section.

5. In a typewriting machine, the combination of a platen frame, a pair of platen sections mounted end to end and having the 95 same axis of rotation, ratchet wheels, one operatively connected with each of said platen sections, and line spacing devices co-operative with said ratchet wheels, each of said line spacing devices comprising a hand 100 operated lever, said levers being operative in opposite directions.

6. In a typewriting machine, the combination of a platen frame, a pair of platen sections mounted end to end and having the 105 same axis of rotation, ratchet wheels, one operatively connected with each of said platen sections, and line spacing devices co-operative with said ratchet wheels, each of said line spacing devices comprising a hand 110 operated lever, said levers being unequal in length and operative in opposite directions.

Signed at Pittsburg, in the county of Allegheny and State of Pennsylvania, this 16th day of December A. D. 1904.

ALFRED F. SMITH.
